W. D. MITCHELL

SMOKE PROTECTOR

Filed June 2, 1926

Inventor
W. D. MITCHELL,

By
Lacey & Lacey, Attorneys

UNITED STATES PATENT OFFICE.

WILLIAM D. MITCHELL, OF SPARTANBURG, SOUTH CAROLINA.

SMOKE PROTECTOR.

Application filed June 2, 1926. Serial No. 113,248.

The invention relates to an appliance which admits of respiration in an otherwise intolerable atmosphere laden with smoke, gas and noxious odors.

5 The invention provides a device of compact form to be readily carried in the pocket so as to be readily at hand in an emergency to admit of a person passing through smoke or other impure atmosphere without suffering ill effects.

10 While the drawings illustrate a preferred embodiment of the invention, it is to be understood that in adapting the means to meet specific needs and requirements, the 15 design may be varied and such other changes in the minor details of construction may be resorted to within the scope of the invention as claimed, without departing from the spirit thereof.

20 For a full understanding of the invention and the merits thereof, reference is to be had to the following description and the drawings hereto attached, in which—

25 Figure 1 is a perspective view illustrative of the application of an embodiment of the invention,

Figure 2 is a vertical, central, longitudinal sectional view of the smoke protector,

30 Figure 3 is a horizontal sectional view on the line 3—3 of Figure 1, looking in the direction of the arrows, and

Figure 4 is a detail perspective view of the spring nose frame.

35 Corresponding and like parts are referred to in the following description and designated in the several views of the drawings by like reference characters.

40 The device comprises a casing 1 of approximately pyramidal form and open at opposite ends and adapted to be arranged with the larger end opposite and in contact with the face, as shown most clearly in Figure 1, and with the smaller end facing outwardly. In the preferable construction, the casing 1 consists of sheet metal which is light and durable. The larger end of the casing 1 is cut away to obtain a close fit against the face and the enclosing walls have an inner flange 2 at their outer 45 ends and an inner flange 3 at the inner ends, the flange 2 serving to retain sponge 4, or analogous material within the casing. The flange 3 serves to partly close the inner or large end of the casing and provides for attachment thereto of a screen or wire gauze 5 which supports the sponge 4, or other suit-

able material and prevents the same from being drawn into the lungs during respiration when the device is in active operation. The inner marginal portion of the flange 3 60 is deflected, as shown most clearly in Figures 2 and 3, and the wire screen 5 is attached to the deflected portion of the flange in any preferred way, as by being soldered thereto. A suitable packing 6, such as felt, 65 is attached to the outer side of that portion of the flange 3 destined to make contact with the face to insure a close fit and obviate injurious pressure. Loops 7 are provided at opposite sides of the casing 1 adjacent the inner end, and receive an elastic 70 8 or other attaching means provided for holding the device in position upon the face, as indicated most clearly in Figure 1.

75 The casing is designed to fit against the face opposite the mouth and below the nose and in order that the user may breathe through the nose, or mouth, or both, as required, the top wall of the casing is provided with openings 9 in position to register 80 with the nostrils upon opposite sides of the septum. To obtain a close fit between the nose of the user and the casing 1 a cover 10 is provided and this cover envelops the nose and is attached to the top side of the 85 casing. The cover includes a spring frame and flexible material, such as thin leather, sheet rubber, or the like. The spring frame

90 consists of a single length of spring wire of suitable gage bent into the form substantially as shown, and comprises similar side pieces, each embodying an upright 11, an inclined member 12 and a lower member 13, the side portions of the frame being connected by a curved member 14 which conforms to the cut away portion of the inner end of the casing. The inclined members 12 are disposed in close relation to extend along the bridge of the nose and the lower portion 13 curves to conform to the sides of the nose. 95 The lower ends of the uprights 11 pass loosely through openings formed in the top side of the casing adjacent the inner end, and the frame is of such construction as to maintain the shape of the cover and insure 100 a close fit thereof about the nose. The flexible material covering the nose frame preferably comprises inner and outer plies between which the nose frame is confined, said plies projecting beyond the upright portions 110 11 of the nose frame and secured by stitching. The edge portion of the flexible cov-

ering projecting beyond the upright portions 11 of the spring nose frame, insures a close and comfortable fit between the cover and the nose. The lower portion of the covering 5 is deflected outwardly and is confined by a retainer 15 which is soldered or otherwise secured to the top side of the casing, said retainer 15 consisting of a strip of metal conforming to the outline of the nose, as indicated most clearly in Figure 1.

The sponge 4, or like porous material is saturated with water, and when the air is drawn therethrough in the act of respiration, the impurities are eliminated, so that 15 the person enveloped by smoke or other impure air will not suffer ill effects or experience serious inconvenience, so that an emergency may be successfully combated as an escape or rescue from a burning building.

Having thus described the invention, I claim:

1. A protector of the character specified, comprising a casing, adapted to fit close 25 against the face opposite the mouth and below the nose, means associated with the casing for holding it in place, said casing having an opening in its top side in line with the nostrils, a flexible cover upon the top 30 side of the casing adapted to envelope the nose and secure a close fit between the casing and the nose, a retainer securing the lower edge of the cover to the casing and a spring nose frame consisting of a single wire including similar side pieces and a lower con-

necting member, each of the side pieces comprising an upright at the side of the nose, an inclined member adjacent the bridge of the nose and a member at the lower end of the inclined member engaging the top of 40 the casing and curving to conform to a side of the nose.

2. A smoke protector comprising a casing tapering throughout its length and having its larger end cut away to fit close against 45 the face opposite the mouth and below the nose, a screen at the inner end of the casing, porous material within the outer portion of the casing and prevented from displacement by said screen, said casing having an 50 opening in its top side to register with the nostrils, a cover adapted to envelope the nose, a retainer securing the lower portion of the cover to the top side of the casing, and a spring nose frame within the cover 55 for preserving the shape thereof and consisting of a single wire comprising similar side pieces and a lower connecting member curved forwardly between its ends, each of the side pieces comprising an upright at 60 the side of the nose with its lower end passing through the top of the casing, an inclined member adjacent the bridge of the nose, and a lower member curving laterally from the inclined member to conform to a 65 side of the nose and resting upon the top of the casing.

In testimony whereof I affix my signature.

WILLIAM D. MITCHELL. [I. S.]
